CHARLES WASHINGTON HILL, OF NEW YORK, N. Y.

Letters Patent No. 91,746, dated June 22, 1869.

IMPROVED CORNICE FOR WINDOW-CURTAINS.

The Schedule referred to in these Letters Patent and making part of the same.

To all whom it may concern:

Be it known that I, CHARLES WASHINGTON HILL, of the city, county, and State of New York, have invented certain new and useful Improvements in Cornices; and I do hereby declare the following to be a full, clear, and exact description thereof, which will enable those skilled in the art to make and use the same, reference being had to the accompanying drawing, forming part of this specification, in which the figure represents a perspective front view of my invention.

Similar letters indicate corresponding parts.

This invention consists in a cornice composed of a series of supporting strips, and made to present the profile of the cornice desired, in combination with a covering of veneers, pasteboard, sheet-metal, or any other flexible material, plain or ornamented, in such a manner, that when the covering is attached to said profile-frame, it is compelled to assume the required shape, and a cornice of a highly-ornamental character can be produced with little trouble or expense.

In the drawing—

The letter A designates a frame which may be made of a supporting-strip, a, from which extends a series of ribs, or arms b, as shown. The ribs, or arms are so adjusted, in relation to each other, that they produce a frame of the required profile.

To this profile-frame, I attach a covering, b', of veneers, pasteboard, sheet-metal, or other material of sufficient flexibility and stiffness. By doing so, the covering has to accommodate itself to the shape of the profile-frame, and a cornice of a highly-ornamental character can be produced at a comparatively trifling expense.

What I claim as new, and desire to secure by Letters Patent, is—

A cornice composed of a backing, a, and a facing of flexible material, b', with the interposed ribs b, as herein set forth.

CHARLES W. HILL.
